UNITED STATES PATENT OFFICE.

JOHN HOFMAN, OF ROCHESTER, NEW YORK.

DESIGN FOR A COUNTER OR TABLE LEG.

SPECIFICATION forming part of Design No. 16,916, dated September 28, 1886.

Application filed May 22, 1886. Serial No. 203,047. Term of patent 7 years.

To all whom it may concern:

Be it known that I, JOHN HOFMAN, a citizen of the United States, residing in Rochester, in the county of Monroe and State of New York, 5 have invented and produced a new and original Design for Standards or Legs for Counters, Show-Cases, Tables, and Desks, of which the following is a specification, reference being had to the accompanying drawings, forming part thereof, in which—

Figure 1 is a side view or elevation of my said design; and Fig. 2 is a top or end view thereof.

Heretofore standards or legs for counters, tables, and desks have been made upon pleasing designs, consisting, principally, of arabesque patterns, but with a superabundance of ornamental braces, thereby making the same much more heavy than was necessary.

20 My design consists, essentially, in the light frame-work shown in Fig. 1, including the curved top brace, A A', and the two legs or outer parts of the frame A B C, A' B' C', each of which legs starts from or near an outer end of the top brace. Said legs then approach each other with a curve of short radius until they meet tangentially, either closely or by means of a piece between them, at B B', about one-third

the distance to the bottom of the design. Then, separating at angle to each other, each leg 30 continues straight to the bottom plates, C C', which are distant from each other at about the same distance as the ends of the top brace. From the point B B', where said legs meet, as aforesaid, there is a central bar, D D', dropping perpendicularly and bisecting the angle of the two legs, and to which each leg is joined by curved braces E E. The central bar may be ornamented at each end, as shown in Fig. 1, with cones, acorns, or other suitable ornaments.

The various essential parts of my said design may be ornamented in various ways subordinate to the general design hereinbefore described.

45

I claim—

In a design for legs or standards for counters, show-cases, tables, or desks, the diverging and curved portions A B C and A' B' C', the ornamental central bar, D D', the top brace, A 50 A', and the curved braces E E and E' E', substantially as shown and described.

JOHN HOFMAN.
